(57) **CLAIM**

The ornamental design for an advanced therapy central power control unit illuminator, as shown and described.

DESCRIPTION

FIG. 1 is a front elevational view of an advanced therapy central power control unit illuminator showing our new design;

FIG. 2 is a rear elevational view of thereof;

FIG. 3 is a top view thereof;

FIG. 4 is a bottom view thereof;

FIG. 5 is a right side elevational view thereof;

FIG. 6 is a left side elevational view thereof;

FIG. 7 is a perspective view taken generally from the top, front, right-hand side thereof;

FIG. 8 is a perspective view taken generally from the top, rear, right-hand side thereof;

FIG. 9 is a perspective view taken generally from the bottom, rear, right-hand side thereof; and,

FIG. 10 is a perspective view taken generally from the bottom, rear, left-hand side thereof.

The broken lines represent portions of the advanced therapy central power control unit illuminator that form no part of the claimed design.
